US0D1013233S

(12) **United States Design Patent** (10) **Patent No.:** **US D1,013,233 S**
(45) **Date of Patent:** **** Jan. 30, 2024**

(54) **LAMP**

(71) Applicant: **Qianjun Hong**, Ningbo (CN)

(72) Inventor: **Qianjun Hong**, Ningbo (CN)

(**) Term: **15 Years**

(21) Appl. No.: **29/841,139**

(22) Filed: **Jun. 3, 2022**

(30) **Foreign Application Priority Data**

Dec. 15, 2021 (CN) 202130830388.9

(51) **LOC (14) Cl.** **26-05**

(52) **U.S. Cl.**

USPC **D26/37**; D26/60

(57) **CLAIM**

The ornamental design for a lamp, as shown and described.

DESCRIPTION

FIG. 1 is a first perspective view of a lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the lamp that form no part of the claimed design.

1 Claim, 8 Drawing Sheets
